UNITED STATES PATENT OFFICE.

SMITH OWEN, OF LA CROSSE, WISCONSIN, ASSIGNOR TO THOMAS MORRIS,
OF SAME PLACE.

CLOTHES-RACK.

SPECIFICATION forming part of Letters Patent No. 624,528, dated May 9, 1899.

Application filed January 16, 1899. Serial No. 702,345. (No model.)

To all whom it may concern:

Be it known that I, SMITH OWEN, a citizen of the United States, and a resident of North La Crosse, in the county of La Crosse and State of Wisconsin, have invented certain new and useful Improvements in Clothes-Racks; and I do hereby declare that the following is a full, clear, and exact description of the invention, which will enable others skilled in the art to which it appertains to make and use the same, reference being had to the accompanying drawings, which form a part of this specification.

My invention relates to a clothes-rack for drying clothes which may be secured to a wall or other place and when not in use may be let down, so as to be out of the way.

The object of the invention is to provide improved means for holding the rack in operative position and also to provide an improved construction of hanger-bars by which the clothes to be dried are supported.

The invention consists in the novel construction and combination of parts hereinabove fully described and claimed.

In the accompanying drawings, Figure 1 is a perspective view of a clothes-rack constructed in accordance with my invention. Fig. 2 is a longitudinal section of the same. Fig. 3 is a detail perspective view of plates 12 and 15. Fig. 4 is a horizontal section on the line $\alpha\alpha$ of Fig. 2. Fig. 5 is a detail perspective view of one of the sockets at the ends of the radial bars or hangers.

In the said drawings the reference-numerals 1 and 2 designate two boards hinged or pivoted together, and when in use they occupy positions at right angles to each other. Pivoted to the horizontal board 1 is a segment 3, comprising the curved plates 4, with a space therebetween, the arms 5, formed integral therewith, and the hub 6, through which passes a pin 7, by which the segment is pivotally connected with said board. Located between the plates 4 are the inner ends of a series of bars or hangers 8. Secured to said ends are metal sockets 9, which are pivotally connected with said plates 4 by pivots 10. These sockets consist of metal plates bent around the inner ends of said bars. These bars 8 extend radially outward and serve to carry the clothes to be dried.

Secured to the vertical board 2 is a plate

12, formed with holes 13 and intersecting slots 14, by which the device may be engaged with headed nails in a wall or other object for supporting the rack. At each side of this plate is secured a vertical plate 15, having its inner side bent outwardly at an obtuse angle to the portion secured to the board, forming ways 60 for spring-catches 16, hereinafter described. At the upper ends these plates 15 are formed with curved lugs 17, with which said catches engage. The numeral 18 designates a spring-metal rod, bent over near the center, forming 65 two catches or arms 16, the ends of which are bent or curved outwardly, so as to engage with the lugs 17. The rod is secured to board 1 by staples 19.

When in use, the parts will be in the position shown in Fig. 1, and it will be seen that the segment may be turned to the right or left, carrying the bars or hangers with it, and also that the bars may be turned on their pivots irrespective of the movement of the segment.

By disengaging the catches 16 from the lugs 17 the board 1 may be let down, so as to be out of the way when not in use, the ends of the said catches traveling along the inclined 80 sides of plates 15, so as to prevent them from flying outward. By this construction when the board 1 is again elevated for use said catches will be guided to the lugs by said sides.

Having thus fully described my invention, what I claim is—

In a clothes-rack, the combination with the hinged boards, the segment pivoted to one of said boards, the bars or hangers pivoted to 90 said segment and the spring-catches pivoted to said board and having their ends bent outwardly, of the vertical plates secured to the other board having their inner sides bent at an obtuse angle to the portion attached to the 95 board and formed with lugs at their upper ends with which said catches engage, substantially as described.

In testimony that I claim the foregoing as my own I have hereunto affixed my signature 100 in presence of two witnesses.

SMITH OWEN.
